UNITED STATES PATENT OFFICE.

ALLEN H. PALMERTON, OF INDIANAPOLIS, INDIANA.

WRECKING-FROG.

SPECIFICATION forming part of Letters Patent No. 298,619, dated May 13, 1884.

Application filed December 21, 1883. (No model.)

To all whom it may concern:

Be it known that I, ALLEN H. PALMERTON, a resident of Indianapolis, Indiana, have made certain new and useful Improvements in 5 Wrecking-Frogs, a description of which is set forth in the following specification, reference being made to the accompanying drawings, in the several figures of which like letters indicate like parts.

10 My invention relates to devices for replacing derailed cars upon the tracks, and will be understood from the following description.

In the drawings, Figure 1 represents a perspective view of my device with a pair of 15 trucks nearly replaced upon the track. Fig. 2 is an end view of my device with a pair of trucks in a similar position.

In detail, *r r* are the track-rails; *w w*, the 20 wheels of a derailed truck; *F*, a frog-plate, made of iron, one end wider than the other, and increasing in thickness from the wide to the narrow end, so as to form an incline; and *f* is a projection or flange integral with the 25 plate *F*, formed or raised the entire length of the plate *F* and about midway between the sides, and made, preferably, a little wider at the narrow end of the frog-plate *F* than at the other, making a slight taper, in fact, about one inch in four feet, the object being to strengthen 30 it at the point where the heaviest pressure comes—viz., at the narrow end of the frog-plate. This frog-plate *F* is provided at its wider end with prongs *p*, for driving into and securing the device to a tie. A clamp, *C*, underlying 35 both the rail *r* and plate *F*, clasps the outer flange of the rail, as shown in Fig. 1, the inner end of the clamp fitting into a channel in the side of the frog, as shown in Fig. 2, and when the clamp is put in place the frog *F* is held 40 firmly to the rail at the upper and to the tie at the lower end. An inclined bar, *i*, is placed outside the other rail and secured in place by prongs at each end, which are driven into the ties, this being an old and well-known device. 45 This bar is made thick enough at its upper

end to lift the flange of a wheel above the top of the rail, as shown in Fig. 2.

My device operates as follows: If the truck *w* be derailed, one wheel being between the rails and the other outside, as is frequently 50 the case, (and in every case a car must be lifted and pulled into such position before it can be replaced upon the rails,) the frog-plate *F* and bar *i* being placed in the positions shown in Fig. 1, the thinner ends of each being placed as closely as possible to the wheels, the derailed car is drawn up the incline, the flange *f* being outside the flange of the inner car-wheel, and as the truck is drawn up this flange gradually crowds the tread of the wheel 55 over toward the rail, and at the proper moment, the flange of the other wheel being at that time lifted upon the bar *i* clear of the adjacent rail, the truck is crowded easily and safely over upon the track by the resistance 60 of the flange *f*, and the frog is still in position 65 for any succeeding pair of derailed trucks.

It will be observed that my device operates by the pressure of the flange *f* against the outside of the flange of the car-wheel, which is 70 substantially flat, while other devices operate against the inner or beveled side of the wheel-flange, and under great strain the wheel is pulled or forced over the frog and off the track into the land, and the labor is all lost.

75 What I claim, and desire to secure by Letters Patent, is the following:

1. The frog-plate *F*, provided with the central flange, *f*, in combination with the rail *r* and the clamp *C*, substantially as described. 80

2. The frog-plate *F*, provided with the central flange, *f*, the clamp *C*, the rails *r*, and the inclined bar *i*, all combined substantially as described.

In witness whereof I have hereto set my 85 hand this 13th day of December, 1883.

ALLEN H. PALMERTON.

Witnesses:

C. P. JACOBS,
H. C. ALLEN.
